UNITED STATES PATENT OFFICE.

LUDWIG REICHOLD, OF WINSTED, CONNECTICUT, ASSIGNOR TO THE FITZGERALD MANUFACTURING COMPANY, OF TORRINGTON, CONNECTICUT, A CORPORATION OF CONNECTICUT.

DESIGN FOR A TOASTER OR SIMILAR ARTICLE.

Application filed April 3, 1929. Serial No. 30,748. Term of patent 7 years.

To all whom it may concern:

Be it known that I, LUDWIG REICHOLD, a citizen of the United States, residing at Winsted, in the county of Litchfield, State of Connecticut, have invented a new, original, and ornamental Design for a Toaster or Similar Article, of which the following is a description, reference being had to the accompanying drawing and to the figures of reference marked thereon.

Fig. 1 is a side elevation of the toaster, showing my new design; and

Fig. 2 is a top plan view of the same.

I claim:

The ornamental design for a toaster or similar article as shown.

In testimony whereof, I affix my signature.

LUDWIG REICHOLD.
